UNITED STATES PATENT OFFICE.

ANDREW J. ROSS, OF LOS ANGELES, CALIFORNIA.

WINDOW LOCK.

Application filed April 23, 1924. Serial No. 709,485.

To all whom it may concern:

Be it known that I, ANDREW J. ROSS, a citizen of the United States of America, and a resident of Los Angeles, county of

5 Los Angeles, and State of California, have invented certain new and useful Improvements in Window Locks, of which the following is a full and clear specification.

The object of this invention is to provide 10 a simple window-sash lock which may be operated by a key, thereby rendering the lock substantially burglar-proof.

In the drawing annexed—

15 Fig. 1 is horizontal sectional view showing the device in locked position;

Fig. 2 is a sectional view on the line 2—2 of Fig. 1;

20 Fig. 3 is a sectional view on the line 3—3 of Fig. 1;

Fig. 4 is a detail sectional view on the line 4—4 of Fig. 3;

25 Fig. 5 is a detail perspective view of the key-actuated gear.

On the edge of the sash is set a bolt-tube 10, and in this bolt-tube is arranged to slide a lock-bolt 11 having a rack 12 in the bottom of a slot formed in its shank. Engaging the rack 12 is a pinion 13 formed on the inner end of a tumbler-shaft 14, which 30 is rotatively supported in a non-rotatable barrel 15 extending into the sash at right angles to the bolt-tube 10. The inner end of the barrel 15 is open and the gear-carrying end of the tumbler-shaft extends beyond the barrel and enters a hole in the bolt-tube 10, so that by turning the tumbler-shaft 14 the lock-bolt may be shifted back and forth.

35 The tumbler-shaft 14 is slotted longitudinally, from its outer end inwardly, to receive a flat key 16 by which the tumbler-shaft may be turned. The tumbler-shaft is held against rotation by a pair of leaf-springs 17 fastened to the barrel 15 and 40 having a pin 17' extending through holes therein at opposite sides of the barrel and adapted to snap into the slot in the tumbler-shaft and thereby lock the tumbler-shaft against rotation. When the key is 45 inserted into the slot in the tumbler-shaft, the rounded forward end of the key cams the pins 17' outwardly far enough to release the tumbler-shaft and permit the same to be rotated by the key. It is desirable 50 to provide some means to hold the gear 13 in mesh with the rack; for this purpose, I

provide the inner end of the barrel 15 with lugs 21 which engage under as well as over the bolt-tube 10 and thus hold the gear down in the rack and the bolt-tube interlocked with the barrel. To enable this interlocking of the parts to be accomplished simply, I make the barrel 15 larger in diameter than the bolt-tube 10, so that when the barrel 15 is driven into the hole formed 60 in the sash to receive it, the rounded inner faces of lugs 21 will come against the rounded surface of the bolt-tube 10 and thus embrace the same.

If desired, a coil-spring 22 may be placed 70 behind the bolt 11 to normally force it outwardly. The outer end of the barrel 15 enters a hole in an ornamental escutcheon plate 18. The springs 17 are circular in shape and lie in annular grooves in the 75 barrel. It will be noted that the pins 17', by entering the groove in the key-barrel 14, lock the bolt 11 either in or out. When the bolt 11 is locked in, the sash may be freely run up and down as usual. When 80 it is desired to lock the sash, it is necessary simply to give the key a half-turn or rather merely insert the key to thus release the pins 17' and permit the spring 18 to project the bolt into the recess provided therefor in the window-frame.

85 A series of the bolt-recesses in the window-frame may be provided in order to lock the sash (both upper and lower) in various positions; and when the sash is locked it will 90 be obvious that it cannot be moved without the use of a key capable of withdrawing the bolt. I prefer using plain keys, as shown, but it will be understood that I may use a permutation arrangement, if desired. To 95 lock the sash in an open position, insert the key and turn it to withdraw the bolt; then, while holding the key in the turned position, move the sash to the desired hole and then remove the key to permit the compressed 100 spring 18 to project the bolt and permit the pins 17' to snap into the key-slot to thus lock the bolt in its locking position. Of course, if the bolt when thus released does not strike the desired hole in the series, the 105 sash may be slid up or down until the bolt snaps into it.

110 It will be understood that my lock may be used on doors or other swinging closures.

What I claim is:

1. In a sash lock of the type set forth,

a bolt-barrel set in the edge of the sash and enclosing a lock-bolt provided with a rack, a tumbler-barrel extending into the face of the sash at right angles to the aforesaid bolt-barrel and having its inner end open, a tumbler-shaft longitudinally slotted for a key and provided with a gear at its inner end, and a spring device carried by the said tumbler-barrel for locking the tumbler-shaft against rotation normally engaging in said key-slot and adapted to be disengaged by the key when the same is inserted, said spring device embodying a flat spring lying in a channel in the exterior of the tumbler-barrel and having a pin extending through the wall of the tumbler-barrel and entering said key-slot.

2. In a sash lock of the type set forth, a bolt-barrel set in the edge of the sash and enclosing a lock-bolt provided with a rack, a tumbler-barrel extending into the face of the sash at right angles to the aforesaid barrel and having its inner end open, a tumbler-shaft longitudinally slotted for a key and provided with a gear at its inner end, and a spring-actuated member carried by the said tumbler-barrel for locking the tumbler-shaft against rotation normally engaging in said key-slot and adapted to be disengaged by the key when the same is inserted, said tumbler-barrel being provided with a lug at its inner end engaging the bolt-barrel.

3. In a sash lock of the type set forth, a bolt-barrel set in the edge of the sash and enclosing a lock-bolt provided with a rack,

a spring for normally projecting the lock-bolt, a tumbler-barrel extending into the face of the sash and having its inner end open, a tumbler-shaft provided with a longitudinal key-slot in its outer end and provided with a gear at its inner end, and a spring carried by the said tumbler-barrel for locking the tumbler-shaft against rotation normally engaging in said key-slot and adapted to be disengaged by the key when the same is inserted, said tumbler-barrel being provided with a pair of lugs at its inner end embracing the bolt-barrel.

4. In a sash lock of the type set forth, a bolt-barrel set in the edge of the sash and enclosing a lock-bolt provided with a rack, a tumbler-barrel extending into the face of the sash at right angles to the aforesaid bolt-barrel and having its inner end open, a tumbler-shaft longitudinally slotted for a key and provided with a gear at its inner end, and a spring device carried by the said tumbler-barrel for locking the tumbler-shaft against rotation normally engaging in said key-slot and adapted to be disengaged by the key when the same is inserted, said spring device consisting of a flat curved spring lying in an annular external channel in the tumbler-barrel and having a pin on its free end which extends through a hole in the tumbler-barrel and engages the key-slot in the path of the key.

In testimony whereof I hereunto affix my signature.

ANDREW J. ROSS.
